FENCE POST CAP

Lloyd Spector, Miami Beach, Fla.

Application August 17, 1954, Serial No. 31,893

Term of patent 14 years

(Cl. D28—1)

Fig. 1

I claim:

The ornamental design for a fence post cap, as shown.
